UNITED STATES PATENT OFFICE.

EDWIN D. WASSELL, OF PITTSBURG, PENNSYLVANIA.

METALLURGIC FURNACE.

SPECIFICATION forming part of Letters Patent No. 285,860, dated October 2, 1883.

Application filed October 20, 1882. (No model.)

To all whom it may concern:

Be it known that I, EDWIN D. WASSELL, of Pittsburgh, in the county of Allegheny, State of Pennsylvania, have invented a certain new and useful Improvement in Metallurgic Furnaces; and I do hereby declare the following to be a full and exact description thereof, reference being had to the accompanying drawings, and to the letters of reference marked thereon.

10 My invention relates to an improvement in metallurgic furnaces; and it consists of a gas-generator combined with heating-flues, air-heating chamber, and a means for purifying of the gases resulting from the combustion of the fuel in said gas-generator, the whole being so arranged, combined, and operating that the gases of the furnace are caused to travel over the crown, down the forward side, under the bottom, up the side next to said air-heating chamber, and then enter the working-chamber in a highly-heated and purified state and mixed with heated atmospheric air.

25 My invention also consists in the peculiar construction of the furnace, whereby a triple reverberatory action of the heat is obtained, and a concentration of it upon the molten metal at the point of its greatest depth, which is at the side opposite to the charging-door and distant from it, all of which will herein-30 after more fully and at large appear.

To enable others skilled in the art with which my invention is most nearly connected to make and use it, I will proceed to describe its construction and operation.

35 In the accompanying drawings, which form part of my specification, Figure 1 represents a vertical longitudinal medium section of my invention; Fig. 2, a horizontal transverse section on line xx ; Fig. 1. Fig. 3, a vertical longitudinal section on line $x'x'$ of Fig. 2. Fig. 4 is a longitudinal transverse vertical section on line 22 , Fig. 3. Fig. 5 is a longitudinal vertical section on line x^2x^2 , Fig. 2. Fig. 6 is a transverse vertical section on line y^2y^2 , Fig. 3. 40 Fig. 7 is a like view on lines $y'y'$, looking toward the stack; and Fig. 8, a like view on line y^2y^2 , looking in the opposite direction.

45 Reference being had to the accompanying drawings, A represents the masonry work of the furnace, and B its metal bindings or stays.

C represents the gas-generator, having a

charging-hopper, D, grate E, and flue F, which communicate with the tubular flue G, which opens into the purifying-chamber H, in the crown of which is arranged a steam-pipe I, 55 which may be connected with any suitable steam-generator.

J represents the air-heating chamber, in which is arranged an elliptic coil of pipe, K, which may be connected with a blast device, 60 and may also communicate with a mechanism for the purpose of carbureting the air in its passage from the blast device to the said pipe K. The elliptic coil of pipe K communicates with a branch pipe, L, having two outlets, M, 65 communicating with a chamber, N, in the bridge-wall O. The purifying-chamber H communicates with two diving-flues, P, which communicate with two horizontal flues, U, arranged under the working-chamber R. Between the flues U, and communicating with the flue T, is an elongated chamber, Q, the side walls of which converge toward the flue T. The horizontal flues U, arranged on each side of the chamber Q, communicate with the vertical flue V, arranged between the air-heating chamber J and the bridge-wall O.

75 By the foregoing arrangement of parts gas is generated, purified, heated, and mixed with the heated atmospheric air or heated and carbureted atmospheric air prior to entering the working-chamber R. The crown W of the working-chamber is inclined downward toward the center of said chamber, as indicated by the arrows marked 3, and is also inclined 80 downward from above the charging-doors X toward the tap-chamber Y, as indicated by the arrow marked 4, the bottom Z of the working-chamber having a similar downward inclination toward said tap-channel. By this 85 arrangement of the bottom Z the greatest depth of the molten metal will be next to the tap-channel and distant from the charging-doors, and with the construction described of the crown W the heat and flame of the furnace will have a triple reverberatory action traveling longitudinally, as indicated by the arrows marked 5, indicating a recoil of the heat and flame which is directed downward on the molten metal in said chamber, and is also 90 reflected toward the charging-doors X.

The skillful furnace-builder and metallurgist

from the foregoing description will readily understand the construction of my improvement in furnaces. I will therefore proceed to describe the operation, which is as follows:

5. The fuel is charged into the gas-generator C in the usual manner and with ordinary means. The gas, as it is generated, passes up through flue or flues F into the tubular flue G, and from it into the purifying-chamber H, where it is subjected to a steam-jet from the pipe I, which steam purifies the gas, and at the same time it is converted into vapor, which, combining with the gas or gases in chamber H, passes down flues P into the horizontal flues u, and from them passes up through vertical flues V and passes over the bridge-wall O; but in its passage over said bridge-wall the heated air, or heated air carbureted, which has entered the chamber N from the elliptic coil of pipe K passes up through a series of small flues, a, and commingles with the highly-heated gases just as they are entering the working-chamber R, thereby insuring a thorough and complete consumption of said gases, and the generation 25 of an intense heat, which is brought to bear and act upon the charge in the working-chamber R in a most thorough manner by the peculiar form of the working-chamber and its crown, hereinbefore described. The heat and flame, 30 after performing its office in the working-chamber R, passes out through opening W into and down through flue T, striking the bottom of said flue. The heat and flame is in part deflected and thrown back into chamber Q, 35 thereby heating the side walls, b, of the horizontal walls U. That part of the heat and flame not deflected passes out through neck c into stack S.

Having thus described the nature, construction, and operation of my improvement, what I claim is—

1. In a metallurgic furnace, the combination of the gas-generator C, tubular flue G, gas-purifying chamber H, flues P U, chamber Q, flue V, and working-chamber R, substantially as herein described, and for the purpose set forth.

2. In a metallurgic furnace, the combination of the gas-generator C, tubular flue G, gas-purifying chamber H, flues P U, chamber Q, flue V, air-heating chamber J, and working-chamber R, substantially as herein described, and for the purpose set forth.

3. In a metallurgic furnace, the combination of the gas-generator C, tubular flue G, gas-purifying chamber H, flues P U, chamber Q, flue V, air-heating chamber J, chamber N, having flues a, and working-chamber R, substantially as herein described, and for the purpose set forth.

4. In a metallurgic furnace, the combination of the gas-generator C, tubular flue G, gas-purifying chamber H, steam-jet I, flues P U, chamber Q, flue V, air-heating chamber J, pipe K, flue N, and working-chamber R, substantially as herein described, and for the purpose set forth.

5. In a metallurgic furnace, the combination of the gas-generator C, tubular flue G, gas-purifying chamber H, steam-jet I, flues P U, chamber Q, flue V, air-heating chamber J, pipe K, flue N, working-chamber R, and flue T, communicating with the neck e and chamber Q, substantially as herein described, and for the purpose set forth.

6. In a metallurgic furnace, the combination of the gas-generator C, tubular flue G, gas-purifying chamber H, flues P U, chamber Q, flue V, and working-chamber R, with the bridge-wall O, and bottom of the working-chamber inclining downward and toward the tap-channel placed on the opposite side of the furnace from the charging-door, substantially as herein described, and for the purpose set forth.

7. In a metallurgic furnace, the combination of the gas-generator C, tubular flue G, gas-purifying chamber H, flues P U, chamber Q, flue V, air-heating chamber J, and working-chamber R, with the bridge-wall O, and bottom of the working-chamber inclining downward and toward the tap-channel placed on the opposite side of the furnace from the charging-door, substantially as herein described, and for the purpose set forth.

8. In a metallurgic furnace, the combination of the gas-generator C, tubular flue G, gas-purifying chamber H, flues P U, chamber Q, flue V, air-heating chamber J, chamber N, having flues a, and working-chamber R, with the bridge-wall O, and bottom of the working-chamber inclining downward and toward the tap-channel placed on the opposite side of the furnace from the charging-door, substantially as herein described, and for the purpose set forth.

9. In a metallurgic furnace, the combination of the gas-generator C, tubular flue G, gas-purifying chamber H, steam-jet I, flues P U, chamber Q, flue V, air-heating chamber J, pipe K, flue N, and working-chamber R, with the bridge-wall O, and bottom of the working-chamber inclining downward and toward the tap-channel placed on the opposite side of the furnace from the charging-door, substantially as herein described, and for the purpose set forth.

10. In a metallurgic furnace, the combination of the gas-generator C, tubular flue G, gas-purifying chamber H, steam-jet I, flues P U, chamber Q, flue V, air-heating chamber J, pipe K, flue N, and working-chamber R, with the bridge-wall O, and bottom of the working-chamber inclining downward and toward the tap-channel placed on the opposite side of the furnace from the charging-door, substantially as herein described, and for the purpose set forth.

E. D. WASSELL.
